WALTER L. MIER, OF OTTUMWA, IOWA.

GRAIN-DOOR DISPLACER.

Application filed March 29, 1926. Serial No. 98,381.

This invention relates to apparatus for displacing the doors of grain cars, and it has for an object the provision of novel means for shearing or cutting the anchorages of the boards or closures employed for holding grain in a car, the said invention being also associated with means for displacing and supporting the displaced closing elements and so nesting the closing elements as to produce a clearance for the escape of grain at the door.

5

While it is now the custom to employ rather heavy lumber, viz: boards of certain dimensions as closing elements and as they are conventionally used, the closing elements are nailed to the car frame or studding, it is within the bounds of possibility that metal or composition closures may be substituted for boards, and hence applicant wishes to be 10 understood as comprehending any of such devices within the term "door elements".

It is an object of this invention furthermore to provide means for adjusting the device laterally with respect to a car and vertically also in order that the apparatus may be properly positioned with respect to the door and actuated to operate to the best advantage after it has been properly positioned; hence, means are provided for moving 25 the door displacer to advance or cause it to recede with respect to the side of the car; and it is furthermore an object to provide means for imparting movement vertically in order that the door elements may be elevated after they have been dislodged.

It is a further object of this invention to produce a door displacer capable of use in association with cars that are on tilting tracks or supports, or cars which are tilted 35 regardless of the manner of their supports, although the device is capable of operation in association with cars that are not tilted.

It is a still further object of this invention to provide means for simultaneously or selectively operating cutters for severing the 45 nails or anchorages by which the door elements are secured in place and the door element dislodging and supporting instrumentalities.

50 It is a still further object of this invention to produce a grain door remover having advantages in points of simplicity, durability and efficiency, and the invention includes other advantages which will be hereinafter 55 more fully set forth in the detailed description of the structure and operation.

In describing the invention in detail, reference will be had to the accompanying drawings forming part of this application wherein like characters denote corresponding parts in the several views, and in which—

Figure 1 illustrates a view in elevation of a door operating device embodying the invention;

Figure 2 illustrates a view in elevation of the rear thereof;

Figure 3 illustrates an enlarged sectional view on the line 3—3 of Fig. 1, omitting the door element displacer and support;

Figure 4 illustrates a detail view of the 70 shear operating gearing;

Figure 5 illustrates a sectional view of a fragment of the face or front plate; and

Figure 6 illustrates an enlarged detail view of the clutch mechanism.

In the present embodiment of the invention, a grain car body 15 is conventionally shown in section and the track 16 may be of the tilting type, by which the car is tilted to displace grain therein.

A frame for supporting the mechanism of the invention may include channel irons 17 that may be supported on suitable posts or other devices, which those skilled in the art will supply without the exercise of invention, the said frame being also associated with a chute 18 which will receive grain from the grain discharging opening in the car after the door is removed, although obviously, the chute may be omitted and other means may be supplied for receiving the grain.

The frame has supports 19 for guiding rollers 20, and it is immaterial whether the supports rotate in the frame or the guiding rollers rotate on the supports, but the function of the rollers is to act as guides for the vertically disposed channel elements 21 of a frame of which the cross head 22 is a part, the said cross head, in the present embodiment of the invention, constituting an anchorage for the piston rod 23 that operates in a cylinder 24, which cylinder may be provided with a piston mounted on the piston rod in order that the frame may be moved vertically under the action of an expandable force admitted to the cylinder, but the inventor does not wish to be limited with respect to the force employed, or the manner of its control, since those are well known expedients and it is enough for the purpose 110 of this disclosure to say that it is the object of the inventor to utilize the mechanism

for raising and lowering the frame in order that the track or platform 25 carried by the side elements 21 may be raised and lowered with respect to the car.

Approximately horizontally disposed tracks or channel elements 26 are attached one to each of the upright members 21 by suitable fastenings 27 such as rivets or the like, and hence as the frame, of which the upright members 21 are a part, is elevated, the track is likewise elevated. The tracks or channel members 26 are connected below at their ends by a plate or tie 28.

A cylinder 29 is applied to mountings or supports 30 and 31 on the tracks 26, and the said cylinder is intended to operate in conjunction with an ordinary piston from which a piston rod 32 projects, the said piston rod being hingedly connected to a follower or front plate 33 which is intended to be forced against the closure members when the grain door is to be removed. Preferably the plate 33 is provided with a plurality of anchoring elements such as spurs 34 that are preferably formed on the ends of bolts 35 that are threaded in the plate and secured at different positions of adjustment by a jamb nut 36. The inventor does not wish to be limited with respect to the number of spurs employed, but as they are to coact with a plurality of closure members or slabs, they should be distributed throughout the area of the plate to insure an effective anchorage for the work involved. One skilled in the art will understand that the number may be increased or diminished to suit particular requirements. The front or face plate is also associated with side plates 37 which project from the plate at each end thereof, and these side plates have extensions 38 which are applied to the shafts or axles 39 of the wheels 40, which latter travel on the rails or channel members 26.

It is the intention of the inventor that the cylinder 29 shall have conventional means for the supply of fluid under pressure in order that a piston therein may be displaced in one or another direction for projecting or retracting the piston rod and for likewise communicating motion to the frame, which includes the face and side plates that have just been described and on which the cutters and the door element dispensing means and their operating parts are mounted.

A suitable beam 41 may be supported between the side plates on which a motor 42 will be stationed, and the motor may be of any appropriate type, preferably electrically driven, although when the device is to be used where current cannot be had, any type of motor or engine may be employed. The motor is here shown as having a shaft 42^a on which a pinion 43 is secured, the said

pinion meshing with a gear wheel 44 on a shaft 45 journaled in appropriate bearings 46 on the side plates. The shaft 45 has a worm 47 at or approximately centrally its length and the worm is engaged by a worm wheel 48 on a shaft 49, which shaft is disposed at right angles to the shaft 45 and it is journaled in appropriate bearings. The shaft 49 has a clutch member 50 splined on it and the said shaft 49 rotates in a clutch member 51 on the hub of which latter clutch member sprocket teeth 52 are carried. The clutch member 50 is moved longitudinally of the shaft by the usual forked lever 50^a, and as this is of conventional type, further illustration thereof is believed to be unnecessary. The clutch member 51 is also associated with and rotates a pinion wheel 53 whose teeth operate in conjunction with the teeth of the oppositely disposed racks 54 and 55 of the arms 56 and 57, respectively. A sprocket chain 58 operates over the teeth 53 and around a sprocket wheel 59 of a shaft 60 near the bottoms of the side plates. A pinion 61 is rotatable with the shaft 60 and its teeth engage the teeth of the racks 62 and 63 of the arms 64 and 65, respectively. The arms 56 and 64 carry a vertically disposed knife 66 and the arms 57 and 65 carry a vertically disposed knife 67. The knives are tapered in width from their upper to their lower ends, although they may be oppositely tapered, or both of them may be tapered from their lower to their upper ends to accomplish what the inventor has in mind in giving them a taper. The purpose is to cause the knives to act on nails or anchoring devices by which the door elements are secured to the car frame or studding. By reason of the tapered configuration, the anchoring elements, which will be hereinafter termed "nails," will be practically successively encountered and sheared, so that the resistance afforded by contact of the knives with the said nails will be distributed over a wider range of movement of the knives than would occur if the knife edges were straight.

Within the run of the chain 58, a sprocket wheel 68 is caused to engage the links of the sprocket chain, and the said sprocket wheel 68 is mounted on a shaft 69 having a beveled pinion 70 which drives a beveled wheel 71 on the shaft 72 which is journaled in appropriate manner in the side plates.

The beveled gear wheel 71 rotates freely on the shaft 72 but it is provided with a clutch member 71^a that coacts with a clutch member 71^b that is splined on the shaft 72. The clutch member 71^b is operated by the usual clutch shifting lever 71^c of appropriate type, and when the clutch members 71^a and 71^b are engaged, the shaft 72 will be rotated, whereas when they are out of engagement, the gear wheel 71 will rotate on 130

the shaft without communicating motion to the shaft 72.

In the operation of the device, the mechanism is driven to project the blades for shearing the anchors of the door members, and while this operation takes place, the gear 71 idles on its shaft. The mechanism is then set and operated to retract the shearing blades and the clutch members 71^a and 71^b are adjusted to operate the shaft 72 when the gear wheel 70 is rotated. After the cutting blades have been retracted, the mechanism is again driven through the motor, and at this operation the curved bars will be projected to dislodge the door members, as will be hereinafter described.

At each end or near each end of the shaft 72 there is a pinion 73 meshing with a gear wheel 74. Each of the wheels 74 is rotatable on a stud or pin 75 on a side plate and each of the gear wheels 74 engages the teeth of a segmental rack 76 formed as a part of a prying and supporting bar 77. Each bar 77 is preferably provided with a tapered end 25 and these bars operate to displace the lowermost door element to force it inwardly and upwardly in order that the said door element may be deposited on and carried by the bar as it is projected, through the gearing just described, in an arc in order that the bars will successively dislodge the door elements and support them while grain is being run from the car. Preferably in operation, after the door elements have been dislodged, 30 the frame and the parts carried thereby are elevated for the purpose of carrying the door elements further up within the car body to increase the clearance for the escape of grain, and when the apparatus is operated to lower the frame and the parts carried by it and the gearing is operated to restore the arms to their inoperative positions, the arms will be withdrawn from the door elements and they will be left in the car with the removal of the arms.

The arms are guided by breast plates or flanges 78 and by anti-friction rollers 79; hence, the segmental racks of the arms will be held in engagement with the operating pinions throughout the movement of the said arms.

The clutch member 50 may be operated with relation to the clutch member 51 by means of a lever 51^a and the lever 51^a may be operated through a cylinder 51^b having an appropriate piston and a piston rod 51^c extending therefrom, the piston to be operated in the cylinder by conventional types of pressure, as those skilled in the art will understand.

The blades of the shears should preferably be constructed with their sides parallel in order that they will have no wedging action. The arms and the racks thereon that en-

gage the pinions 53 and 61 are guided by 65 ribs 80 on the face of the plate 33.

As the operation of the different elements has been ascribed to them in connection with a description of the said elements, a résumé of the operation of the device as a whole is 70 believed unnecessary to an understanding of the invention by one skilled in the art.

I claim:

1. In a grain door displacer, means comprising curved bars for displacing and supporting grain door elements, and means for projecting, elevating and retracting the said bars.

2. In a grain door displacer, means comprising curved bars for displacing and supporting grain door elements, means for moving the bars longitudinally and projecting and retracting the same, and means for elevating and lowering said bars.

3. In a grain door displacer, a mounting 85 for operating mechanism, means for movably supporting the mounting whereby it may be projected and retracted with relation to a car, displacing and supporting means for door elements operatively applied to the 90 mounting and mechanism for operating the said means.

4. In a grain door displacer, a mounting for operating mechanism, means for movably supporting the mounting whereby it 95 may be projected and retracted with relation to a car, displacing and supporting means for door elements operatively applied to the mounting, mechanism for operating the said means, and means for elevating and 100 lowering the mounting.

5. In a grain door displacer, a mounting, means for supporting the mounting for movement with relation to a car door, shearing blades applied to the mounting for 105 movement toward and away from each other, means on the mounting for displacing door elements, and mechanism for operating the shears and the last mentioned means simultaneously.

6. In a grain door displacer, a front plate and side plates extending from the ends of the front plate, means for holding the side plates in assembled relation to each other, a carriage on which the assembled plates are mounted, means for elevating and lowering the carriage, rack bars mounted for movement on the rear face of the front plate and projecting from opposite ends thereof, shearing blades carried by the bars, door element displacing means operatively mounted on the side plates, and mechanism for actuating the last mentioned means and the rack bars in unison.

7. In a grain door displacer, a front plate and side plates extending from the ends of the front plate, means for holding the side plates in assembled relation to each other,

- a carriage on which the assembled plates are mounted, means for elevating and lowering the carriage, rack bars mounted for movement on the rear face of the front plate and 5 projecting from opposite ends thereof, shearing blades carried by the bars, door element displacing means operatively mounted on the side plates, mechanism for actuating the last mentioned means and the rack bars in unison, and spurs projecting from the outer face of the front plate.
8. In a grain door displacer, a mounting comprising a front plate and side plates extending parallel from the ends thereof, 15 means for holding the side plates in assembled relation to each other, curved guides on the side plates, curved bars each including a segmental rack movable in engagement with the guides and in position for their 20 ends to be projected beyond the face of the plate, pinions engaging the racks, means for rotating the pinions oppositely, and means for retaining the front plate in engagement with grain door elements.
- 25 9. In a grain door displacer, a mounting comprising a front plate and side plates extending parallel from the ends thereof, means for holding the side plates in assembled relation to each other, curved guides 30 on the side plates, curved bars each including a segmental rack movable in engagement with the guides and in position for their ends to be projected beyond the face of the plate, pinions engaging the racks, 35 means for rotating the pinions oppositely, shearing blades mounted for movement in a plane parallel with the plane of the plate, and means for retaining the front plate in engagement with grain door elements.
- 40 10. In a grain door displacer, a front plate adapted to be held in operative relation to a grain door, shearing blades mounted for movement transversely of and beyond the ends of the plate, the cutting edges of the 45 shearing blades being diagonal with respect to the position of the elements which they shear, means for projecting and retracting the blades, and door element displacing devices operated simultaneously with the said shears.
- 50 11. In a grain door displacer, a front plate adapted to be held in operative relation to a grain door, shearing blades mounted for movement transversely of and beyond the ends of the plate, the cutting edges of the 55 shearing blades being diagonal with respect to the position of the elements which they shear, means for projecting and retracting the blades, door element displacing devices operated simultaneously with the said shears, the said displacing devices comprising curved bars, and guides for causing the ends of the devices to project 60 beyond the front plate.
- 65 12. In a grain door displacer, mechanism adapted to be stationed in operative relation to a grain door including shearing blades for severing the anchors of the door elements, the cutting edges of the shearing 70 blades being diagonal with respect to the position of the elements which they shear, means for projecting and retracting the shearing blades, and means for displacing and supporting the door elements in elevated 75 positions with respect to the positions of the door elements when anchored.
- 80 13. In a grain door displacer, curved bars, curved guides in which the bars are movable, and means for projecting and retracting the curved bars in engagement with their guides.
- 85 14. In a grain door displacer, curved bars, curved guides in which the bars are movable, means for projecting and retracting the curved bars in engagement with their guides, and means for elevating the structure including the bars and guides.

WALTER L. MIER.
